CLAIM

The ornamental design for a lift truck body, substantially as shown and described.

DESCRIPTION

FIG. 1 is a front perspective view of a lift truck body showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a rear perspective view thereof;

FIG. 8 is a front perspective view of a lift truck body showing a second embodiment;

FIG. 9 is a right side elevational view of FIG. 8;

FIG. 10 is a left side elevational view of FIG. 8;

FIG. 11 is a front elevational view of FIG. 8;

FIG. 12 is a rear elevational view of FIG. 8;

FIG. 13 is a top plan view of FIG. 8;

FIG. 14 is a rear perspective view of FIG. 8.

The broken lines shown in FIGS. 1 through 15 are for illustrative purposes only and form no part of the claimed design
